Application December 8, 1950, Serial No. 199,825

7 Claims. (Cl. 179—171)

1

My invention relates to generators of radio-frequency power using electron tubes, and more particularly to high-power generators using tetrodes.

An object of my invention is to provide an improved R. F. generator employing cavity type resonators and incorporating a plurality of electron tubes for delivering large orders of power in the higher frequency ranges, say above 100 mcs./sec.

Another object is to provide an R. F. generator of the character described in which the electron tubes are tetrodes, thus providing high power gain in the generator.

A still further object is to provide such a generator which may be designated to operate either as an amplifier or as an oscillator.

The invention possesses other objects and features of advantage, some of which with the foregoing, will be set forth in the following description of my invention. It is to be understood that I do not limit myself to this disclosure of species of my invention as I may adopt variant embodiments thereof within the scope of the claims.

Referring to the drawings:

Figure 1 is a vertical sectional view of the improved R. F. generator embodying my invention; and

Figure 2 is a transverse sectional view taken along the plane indicated by line 2—2 of Figure 1.

In terms of broad inclusion the radio-frequency generator comprises a plurality of tetrodes disposed in a circle about an axis and each having an anode and screen grid and control grid and cathode; output and input resonators each comprising an annular cavity extending axially of the circle and having inner and outer conductors, the anode of each tetrode being electrically connected to the inner conductor of the output resonator and the cathode of each tetrode being electrically connected to the inner conductor of the input resonator; means including a condenser coupling the screen grid of each tetrode to the outer conductors of the resonators; and an annular hollow conductor extending axially of the input resonator and encircling the inner conductor thereof, the last mentioned conductor being open at one end and electrically connected to the control grid of each tetrode at the other end. When the apparatus is operated as an amplifier the screen grid condenser functions as an R. F. by-pass condenser and when operated as an oscillator this condenser is designed as a feedback device for feeding energy from the output resonator to the input resonator. An important

feature in my apparatus is the arrangement of the control grid line or conductor within the input resonator, as this is conveniently adaptable for a tetrode structure wherein the control grid terminal naturally lies between the cathode and screen grid terminals.

In greater detail and referring to the drawings, my radio-frequency generator constructed as an amplifier comprises a plurality of tetrodes 1 disposed in a circle about an axis, which tubes are of like construction and have like characteristics. While five tubes are shown, it is understood that any desired number may be employed depending upon the power output required. Tetrodes 1 are of conventional construction having a cathode 2, control grid 3, screen grid 4 and anode 6, the anode being external and all the electrodes being preferably cylindrical and coaxial. The preferred tube used with my circuitry has coaxial terminals for the electrodes, such as the cathode terminal 7 opposite the anode and the control grid terminal ring 8 and screen grid terminal ring 9 interposed in the envelope wall between the cathode terminal and anode. This sequence of terminals on the envelope is a natural and customary terminal arrangement in tetrode type tubes. The heating structure for the cathode is not shown but may comprise any suitable means such as an inner filament for heating the cathode cylinder 2 by electron bombardment, in which case the filament leads preferably extend out through the tubular cathode terminal 7.

The amplifier has an output resonator 11 and an input resonator 12, which resonators comprise annular-shaped cavities that are coaxial with the tube circle and are common to the plurality of tubes 1. Output cavity resonator 11 is made up of an inner annular conductor comprising metal cylinders 13 joined by an end ring 14, and outer conductors comprising metal cylinders 16. These conductors thus form a pair of communicating annular cavity sections 17, the space joining the cavity sections being located adjacent the upper portions of tubes 1. In a like manner the input cavity resonator is made up of an inner annular conductor comprising metal cylinders 18 joined by an end ring 19, and outer conductors comprising metal cylinders 21 which latter cylinders may be integral with the outer cylinders 16 of the output resonator. The conductors of the input resonator also form a pair of communicating annular cavity sections 22, the space joining such cavity sections being located adjacent the lower portions of tubes 1. Thus the annular cavities of the output and

input resonators are concentric with the axis of the tube circle, each cavity being of U-shape in cross-section and common to the plurality of tubes 1. It will also be noted that the main sections 17 and 22 of the output and input cavities extend axially of the tube circle so that the principal propagation in these cavities is axial rather than radial of the tubes.

It will thus be noted that each resonator comprises two cavity sections, each section being constituted by the space between a pair of concentric cylinders. The length of each section, measured axially of the circle of tube units, is substantially greater than the width of the section, measured radially of the circle of tube units, i. e., the difference in radius of the concentric cylinders which define the section (ignoring the thickness of the cylinders). An annulus having a greater axial than radial dimension, measured as described is defined hereinafter as an axially extending annulus.

Anodes 6 of the tetrodes 1 are electrically connected for radio-frequency current to the inner conductor of the output resonator, in the device illustrated this being a direct connection to the end ring 14 which is apertured so that the anodes project upwardly into the hollow inner conductor. Suitable means for cooling the anodes may thus be provided in the open space of the hollow conductor. In a similar manner cathodes 2 of the tetrodes are electrically connected for radio-frequency current to the inner conductor of the input resonator, this being a direct connection to the cathode terminals 7 which project downwardly through the end ring 19 of the hollow conductor. Suitable leads for the cathode heater means of the several tubes may thus extend out through the hollow conductor.

Any suitable metal such as brass may be used for the various conductors described which make up the boundary walls of the cavities. For purposes of mechanical support the inner conductor of the output resonator is fastened to upper rings 23 of insulating material interposed between the cylinders 13 and 16. Likewise the inner conductor of the input resonator is held in position by lower rings 24 of insulating material interposed between the cylinders 18 and 21.

Screen grids 4 of the tetrodes are electrically coupled for radio-frequency current to outer conductors of the resonators. In order to isolate the D. C. screen grid voltage, the coupling includes an R. F. bypass condenser comprising a transverse metal plate 26 connected to the outermost conductors 16 and 21 and a second metal plate or ring 27 connected to screen grid terminal rings 9. These plates are spaced by a suitable insulating layer 28, the capacitance of this bypass condenser in the amplifier being large enough to prevent any appreciable amount of feedback of energy from the output to the input resonator. Member 26 which forms the lower plate of the condenser also comprises the dividing wall between the cavity resonators, it being a metal disk extending transversely across the unit and fastened at the periphery to the outermost conductors 16 and 21 which constitute the shell of the generator. As illustrated, this plate member is apertured to receive the tubes so that the later project partially into the upper cavity and partially into the lower cavity.

From the above structure it will be seen that an output cavity circuit is provided between the anodes and screen grids of the tetrodes, and that an input cavity circuit is provided between

the cathodes and screen grids. In order to establish the third desired circuit for applying the required R. F. voltage between the control grids and cathodes, I provide an annular open ended transmission line within the input resonator. This is conveniently adaptable for tetrode structures wherein the control grid terminals 8 naturally lie between the cathode and screen grid terminals. As shown, the control grids 3 are connected to the closed end of an open ended hollow metal conductor extending axially of the input resonator and encircling the inner conductor thereof. This grid conductor comprises a pair of cylindrical walls 29 joined by an end ring 31 connected to the control grid terminal rings 9, the end ring 31 being apertured to receive the tubes. For purposes of adjusting the axial length of the grid line the side walls of the hollow conductor preferably have slideable sections 32 at the open end. For optimum operation the length of the hollow grid conductor is preferably made equal to an integral number of half wave lengths electrically at the operating frequency.

Adjustable means are provided for tuning the output and input resonators to the desired operating frequency. For this purpose a pair of annular metal plates 33 are provided in sections 17 of the output resonator, on opposite sides of the inner conductor, so as to form the upper end walls of the cavity sections. These plates are slideably mounted on the cylindrical walls 13 of the inner conductor, and axial adjustments is achieved by means of plunger rods 34 of insulating material 35 projecting through supports 23. Rods 34 may be connected externally to insure that plates 33 are adjusted in unison. Plates 33 are connected to the inner conductor only and have cylindrical flanges 36 closely spaced to the wall conductors 16 so that the device also functions as a choke to confine the R. F. and isolate the D. C. anode voltage. For this purpose the flanges 36 of the choke are made effectively a quarter wave long at the operating frequency, telescoping sleeves 45 (not shown) being provided on the flanges if desired to adjust their length. Positive anode potential may thus be applied by direct connection with the inner conductor as indicated at 37. Tuning the output resonator is accomplished by adjusting the end plates 33 to make the cavity sections 17 the desired length for a selected operating frequency, as will be readily understood.

In a like manner a pair of annular plates 38 are provided in the input resonator, adjustable by means of plunger rods 39 for tuning to the desired operating frequency. Here the end plates are in the nature of shorting bars having slideable contact with both the inner conductor walls 18 and the outer conductor walls 21. In the apparatus illustrated the cathodes are operated at ground potential, the positive anode potential being applied by direct connection to the anodes as already mentioned. The control grid bias voltage is supplied from a suitable source, as through a resistor 41, and is connected to grid line 29 by a wire 42 entering the resonator through a suitable R. F. choke 43. In a like manner the screen grid voltage is supplied from a suitable source, as through a resistor 44, and is connected to screen grid ring 27 by a wire 45 entering the resonator through a suitable R. F. choke 46.

R. F. driving power may be fed into the input resonator from a suitable source of drive by any

5

suitable means, as by a loop or probe. The preferred structure however, as illustrated, comprises a centrally located transmission line 47 coupled to the resonator through a slot. Transmission line 47 is made up of an inner conductor 48 terminating at the transverse dividing wall 26 between the resonators, and an outer conductor 49 which is a continuation of the innermost conductor 21 of the input resonator. Energy coupling means between the input line and resonator comprises a circular slot 50 formed by spacing the inner end of conductor 21 from the transverse wall 26. The circular arrangement of this coupling slot is desirable because it provides uniform coupling of energy from the transmission line to the annular cavity 22.

Output power from the amplifier is preferably transferred from the output resonator to a suitable load by means of a transmission line 51 coaxial with the input line, and having an inner conductor 52 terminating at the transverse wall 26 and an outer conductor 56 formed as a continuation of the innermost conductor 16 of the output resonator. A circular slot 57 serves to couple energy from the output resonator to the transmission line 51.

In adjusting the amplifier the output cavity resonator 11 between the anode and screen grid is tuned to resonance at the operating frequency, the plates 33 being adjusted so that the axial length of each cavity section 17 is an odd number of quarter wave lengths electrically. The input cavity resonator 12 between the cathode and screen grid is adjusted by plates 38 so that the length of each cavity section 22 is roughly an integral number of half wave lengths electrically at the operating frequency. As already mentioned the length of the open end grid line 29-32 within the input resonator is also set at approximately an integral number of half wave lengths electrically. By this arrangement, and by the proper adjustment of the lengths of the grid line 29-32 and the input resonator 12, it is possible to achieve the desired amplitude and phases of the R. F. voltages between the cathodes, screen grids and control grids of the tetrodes.

An important feature of my annular cavity type of generator employing a plurality of tubes is that a large amount of R. F. power can be produced at the higher frequencies without undue circuit losses. In my improved apparatus the power amplification is obtained with no greater loss of efficiency as the frequency is raised than would be the case in a single tube amplifier. The total power output, as measured at the load, for a generator having n number of tubes is substantially n times that obtainable from a single tube in an efficient single tube amplifier.

Another important feature of my invention is that the above mentioned advantage of high power generation is attained with tetrode type tubes, so that the other advantages inherent in a tetrode, such as increased power gain, are also had.

While I have described my apparatus as an amplifier, it is understood that the generator may be operated as an oscillator, and that the term generator is employed herein, as is common usage, in the generic sense. In the latter case the input transmission line 47 would be omitted and the capacitance of the condenser 26-27-28 decreased so as to provide sufficient feedback of energy from the output resonator 11 to the input or excitation resonator 12 to

6

sustain oscillation. Thus, in the oscillator case, the condenser associated with the screen grid would function as a feedback condenser rather than a bypass condenser. In other respects the structure of the R. F. generator would remain unchanged.

For purposes of illustration I have shown the output resonator arranged end-to-end with the input resonator. If it were desirable to have a more compact construction the output cavity sections could be folded back over the input resonator as will be readily understood by those skilled in the art.

I claim:

15. 1. A radio-frequency generator comprising a plurality of tetrodes disposed in a circle about an axis and each having an anode and screen grid and control grid and cathode, output and input resonators each comprising an annular cavity extending axially of said circle and having inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, and an annular hollow conductor extending axially of the input resonator and encircling the inner conductor thereof, said hollow conductor being open at one end and electrically connected to the control grid of each tetrode at the other end.
20. 2. A radio-frequency generator comprising a plurality of tetrodes disposed in a circle about an axis and each having an anode and screen grid and control grid and cathode, output and input resonators each comprising an annular cavity extending axially of said circle and having inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, and an annular hollow conductor extending axially of the input resonator and encircling the inner conductor thereof, said hollow conductor being open at one end and electrically connected to the control grid of each tetrode at the other end.
25. 3. A radio-frequency generator comprising a plurality of tetrodes disposed in a circle about an axis and each having an anode and screen grid and control grid and cathode, output and input resonators each comprising an annular cavity extending axially of said circle and having inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, and an annular hollow conductor extending axially of the input resonator and encircling the inner conductor thereof, said hollow conductor being open at one end and electrically connected to the control grid of each tetrode at the other end, the last mentioned conductor comprising telescoping sections for adjusting the length thereof.
30. 4. A radio-frequency generator comprising a plurality of tetrodes disposed in a circle about an axis and each having an anode and screen grid and control grid and cathode, output and input resonators each comprising an annular cavity extending axially of said circle and having inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, and an annular hollow conductor extending axially of the input resonator and encircling the inner conductor thereof, said hollow conductor being open at one end and electrically connected to the control grid of each tetrode at the other end, the last mentioned conductor comprising telescoping sections for adjusting the length thereof.
35. 5. A radio-frequency generator comprising a plurality of tetrodes disposed in a circle about an axis and each having an anode and screen grid and control grid and cathode, output and input resonators each comprising an annular cavity extending axially of said circle and having inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, and an annular hollow conductor extending axially of the input resonator and encircling the inner conductor thereof, said hollow conductor being open at one end and electrically connected to the control grid of each tetrode at the other end, the last mentioned conductor comprising telescoping sections for adjusting the length thereof.
40. 6. A radio-frequency generator comprising a plurality of tetrodes disposed in a circle about an axis and each having an anode and screen grid and control grid and cathode, output and input resonators each comprising an annular cavity extending axially of said circle and having inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, and an annular hollow conductor extending axially of the input resonator and encircling the inner conductor thereof, said hollow conductor being open at one end and electrically connected to the control grid of each tetrode at the other end, the last mentioned conductor comprising telescoping sections for adjusting the length thereof.
45. 7. A radio-frequency generator comprising a plurality of tetrodes disposed in a circle about an axis and each having an anode and screen grid and control grid and cathode, output and input resonators each comprising an annular cavity extending axially of said circle and having inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, and an annular hollow conductor extending axially of the input resonator and encircling the inner conductor thereof, said hollow conductor being open at one end and electrically connected to the control grid of each tetrode at the other end, the last mentioned conductor comprising telescoping sections for adjusting the length thereof.
50. 8. A radio-frequency generator comprising a plurality of tetrodes disposed in a circle about an axis and each having an anode and screen grid and control grid and cathode, output and input resonators each comprising an annular cavity extending axially of said circle and having inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, and an annular hollow conductor extending axially of the input resonator and encircling the inner conductor thereof, said hollow conductor being open at one end and electrically connected to the control grid of each tetrode at the other end, the last mentioned conductor comprising telescoping sections for adjusting the length thereof.
55. 9. A radio-frequency generator comprising a plurality of tetrodes disposed in a circle about an axis and each having an anode and screen grid and control grid and cathode, output and input resonators each comprising an annular cavity extending axially of said circle and having inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, and an annular hollow conductor extending axially of the input resonator and encircling the inner conductor thereof, said hollow conductor being open at one end and electrically connected to the control grid of each tetrode at the other end, the last mentioned conductor comprising telescoping sections for adjusting the length thereof.
60. 10. A radio-frequency generator comprising a plurality of tetrodes disposed in a circle about an axis and each having an anode and screen grid and control grid and cathode, output and input resonators each comprising an annular cavity extending axially of said circle and having inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, and an annular hollow conductor extending axially of the input resonator and encircling the inner conductor thereof, said hollow conductor being open at one end and electrically connected to the control grid of each tetrode at the other end, the last mentioned conductor comprising telescoping sections for adjusting the length thereof.
65. 11. A radio-frequency generator comprising a plurality of tetrodes disposed in a circle about an axis and each having an anode and screen grid and control grid and cathode, output and input resonators each comprising an annular cavity extending axially of said circle and having inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, and an annular hollow conductor extending axially of the input resonator and encircling the inner conductor thereof, said hollow conductor being open at one end and electrically connected to the control grid of each tetrode at the other end, the last mentioned conductor comprising telescoping sections for adjusting the length thereof.
70. 12. A radio-frequency generator comprising a plurality of tetrodes disposed in a circle about an axis and each having an anode and screen grid and control grid and cathode, output and input resonators each comprising an annular cavity extending axially of said circle and having inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, and an annular hollow conductor extending axially of the input resonator and encircling the inner conductor thereof, said hollow conductor being open at one end and electrically connected to the control grid of each tetrode at the other end, the last mentioned conductor comprising telescoping sections for adjusting the length thereof.

at one end and electrically connected to the control grid of each tetrode at the other end, and tuning means in the output and input resonators for adjusting the axial length of said resonators.

4. A radio-frequency generator comprising a plurality of tetrodes disposed in a circle about an axis and each having an anode and screen grid and control grid and cathode, output and input resonators each comprising an annular cavity extending axially of said circle and having inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, said coupling means including a condenser, and an annular hollow conductor extending axially of the input resonator and encircling the inner conductor thereof, said hollow conductor being open at one end and electrically connected to the control grid of each tetrode at the other end.

5. A radio-frequency generator comprising a plurality of tetrodes disposed in a circle about an axis and each having an anode and screen grid and control grid and cathode, output and input resonators each comprising an annular cavity extending axially of said circle and having inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, said coupling means including a condenser plate connected to the outer conductors of the resonators and a second condenser plate spaced from the first plate and connected to a screen grid of each tetrode, and an annular hollow conductor extending axially of the input resonator and encircling the inner conductor thereof, said hollow conductor being open at one end and electrically connected to the control grid of each tetrode at the other end.

6. A radio-frequency generator comprising a plurality of tetrodes disposed in a circle about an axis and each having an anode and screen grid and control grid and cathode, output and input resonators each comprising an annular cavity extending axially of said circle and hav-

ing inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, an annular hollow conductor extending axially of the input resonator and encircling the inner conductor thereof, said hollow conductor being open at one end and electrically connected to the control grid of each tetrode at the other end, an output transmission line extending axially of said circle, and energy coupling means comprising a circular slot communicating between said output line and output resonator.

7. A radio-frequency generator comprising a plurality of tetrodes disposed in a circle about an axis and each having an anode and screen grid and control grid and cathode, output and input resonators each comprising an annular cavity extending axially of said circle and having inner and outer conductors, the axial dimension of said resonator being substantially greater than the radial dimension thereof, the anode of each tetrode being electrically connected to the inner conductor of the output resonator and the cathode of each tetrode being electrically connected to the inner conductor of the input resonator, means coupling the screen grid of each tetrode to the outer conductors of the resonators, an annular hollow conductor extending axially of the input resonator and encircling the inner conductor thereof, said hollow conductor being open at one end and electrically connected to the control grid of each tetrode at the other end, an output transmission line extending axially of said circle, energy coupling means comprising a circular slot communicating between said output line and output resonator, an input transmission line extending axially of said circle, and energy coupling means comprising a circular slot communicating between said input line and input resonator.
